UNITED STATES PATENT OFFICE.

CHARLES HENRI CLAUDEL, OF PARIS, FRANCE.

CARBURETER.

1,073,473.

Specification of Letters Patent. Patented Sept. 16, 1913.

Application filed April 20, 1907. Serial No. 369,379.

To all whom it may concern:

Be it known that I, CHARLES HENRI CLAUDEL, a citizen of the Republic of France, residing at 11 Rue de Berri, Paris, in the Republic of France, engineer, have invented certain new and useful Improvements in Carbureters, of which the following is a specification.

This invention relates generally to carbureters of the type comprising a carbureting chamber having a variable outlet port or throttle, a variable pure air inlet port, and means for delivering preferably heated liquid fuel to a point between the two ports at a rate dependent upon the degree of vacuum produced at such point of delivery, by the pumping action of the engine.

The invention relates more particularly to the special class of the type of carbureters thus defined, in which the throttle and air valves are slides rigidly connected to move as one part, in fact, as the plug of a simple plug cock in the preferred form, so that the set of the air slide is solely dependent upon the set given to the throttle; and the object of the invention is to secure the desirable unequally varying series of air port areas which correspond to a given uniformly varying series of throttle areas without necessitating any change in the uniform rate of speed of the two connected slides.

To this end the invention consists in securing variations in the area of the air port, exactly similar to such as might be produced by changes in speed of the air slide by means of suitable changes in the shape of the inlet closing edges as compared with the shape of the outlet closing edges.

It is old in the art (Parmenter, U. S. Patent 771,492 of 1904, for instance) to secure a series of air inlet areas corresponding to a differently varying series of mixture outlet areas, by causing two similar valves to be moved at different rates by what Willis in his "Principles of Mechanism" terms a "varying-velocity-ratio-mechanism"; and the object of the present invention in its broadest aspect is to accomplish with two valves rigidly connected as one, with a single valve of the plug valve type, for instance, what was thus heretofore done more or less perfectly by the use of the two separate valves.

Devices such as Parmenter's just referred to surely permit of securing two desired air

inlet areas corresponding to two given values of the outlet area, but all other values of the air inlet obtained will depend upon the law controlling the operation of the varying-velocity-ratio-mechanism used to connect the valves mechanically. A properly designed cam used in Parmenter, however, would permit of securing any desirable series of air port areas, so that the present invention permits of doing what could only be done in Parmenter with such cam and the plotting of a valve is no more difficult than the plotting of a cam. The Claudel valve itself may, in fact, be considered as a cam, so perfectly suited to its purpose that it dispenses with all intermediate mechanism.

As a given area may have any desired shape, the invention permits of selecting a shape for the active or port closing edge of the air slide that will provide a radial passage for the fuel jet; and that will also secure a desirable distribution of the air streams around the jet when the air port area is reduced to its minimum value.

While the invention as defined above evidently permits of securing any desired corresponding series of air port areas, with even more certainty than can be done by means of mechanically connected valves moving at different rates, the shape shown in the annexed drawing acts to retard closure of the air valve in the first stages of closure and to accelerate it in the later stages (which stop short of full closure) while the outlet port area is decreased in arithmetical progression from full opening to full closure; and this law of action is general.

A series of corresponding throttle and air port areas is determined experimentally, as well understood in the art, by the use of an independently movable throttle and an independently movable air valve to permit of finding the air port values that secure the most satisfactory operation of the engine under the normal conditions of the test. The engine, however, will race more or less above the normal speed for which it may be set by the throttle, whenever it meets with a relatively low resistance. This racing exerts a violent pumping action which tends to produce an excessively rich mixture, and the invention, therefore, further consists in providing automatic means for preventing the formation of such richer mixtures.

The positively acting, hand- or governor controlled, throttle and air slide, on the one hand, and the automatic regulator for accidental higher speeds at all sets of the 5 throttle, on the other hand, are thus seen to coöperate, in securing approximately constant carburation; that is, coöperate to prevent any variation in carburation that might be sufficiently great to interfere with the 10 satisfactory operation of the engine under all working conditions.

The invention, furthermore, consists in certain minor features, as will appear in the following description and in the appended 15 claims.

A tested structural embodiment of the invention in which the two connected port controlling slides are the diametrically opposite ends of the bore in a plain plug cock 20 is shown in the accompanying drawings, where:

Figure 1 is a vertical section of plug and casing in a plane perpendicular to the axis of rotation of the plug; Fig. 2 is a section 25 on line 2—2 of Fig. 1, the bore of the plug being brought back into vertical position; Figs. 3 and 4 are diagrammatic sections on the lines 3—3 and 4—4 of Fig. 4, respectively, showing the different form of the two 30 slide openings adapted to secure the desired differentially varying series of port areas; and Fig. 5 is a sectional view showing a modified form.

In the cylindrical cock casing *a*, which may 35 be of any other form having its inner slide wall shaped as a surface of revolution, is fitted and adapted to revolve the correspondingly shaped plug *b* which is held in its different angular positions or sets by hand, 40 or else automatically by the governor.

The bore *c* of the plug *b* constitutes the main wall of the carbureting chamber which is thus seen to be a movable chamber adapted to be set at different positions with relation to its stationary surrounding valve casing *a*. As casing *a*, however, is stationary, and may equally well be referred to as the wall or limit of the carbureting space *c*; and, moreover, as a port opening of the kind 50 here considered depends equally upon the shape of both coöoperating openings, it will facilitate the comprehension of this invention to restrict the use of the term chamber to the confined space *c* itself, to call openings in the wall of casing *a* ports, and the coöoperating openings in plug *b* slide openings; it being understood once for all that slide openings may also properly be designated as port openings. The carbureting 55 space or chamber *c*, therefore, has a circular pure air inlet port *e'*, and a similar mixture outlet port *f'*, both leading through the wall of casing *a*. The mixture outlet port *f'* is controlled by the circular outlet slide opening *f*, while air inlet port *e'* is controlled by

the very differently shaped inlet slide opening *e*. The shape of the opening *e* is such, as before explained, as to reserve a certain air inlet area when the outlet is fully closed, and this reserve space, as clearly seen in Fig. 4, is formed as a diametral channel with enlarged pocket at its end. The diametral channel provides a space for leading the fuel jet *d* up through the air port *e'*, into the carbureting chamber *c*, and the enlarged end or pocket provides a concentric distribution of entering air streams about the jet when the valve is in its position of greatest closure. As long as the pocket of the diametral channel remains covered by the wall of casing *a*, the channel, being relatively wide, acts to retard closure materially, but not sufficiently, and for this reason the lateral angular recesses *R*, *R* are provided as seen in Fig. 4. These recesses *R*, *R* are formed in a part of the air slide that is covered when the slide is in either extreme position, but that appears in the air port *e'* when the air slide is moved from full open to extreme closed position. As a result these recesses retard the first stages of the closing action and accelerate the later stages; that is, as compared with what closure would be if the air slide opening *e* were of the same shape as the outlet slide. The port openings 95 may be of any preferred form, and the slide openings that coöperate with them may also be of any preferred forms; but, as just seen, it is the differences in form of the outlet and inlet port areas which produce the desired 100 differential effects.

Above the injector *d*, Figs. 1 and 2, is arranged a baffle *g*, which may be a plain rod as shown or formed of any other suitable plane, conical, spherical or cylindrical shape. 105 This baffle may be arranged in a fixed position relatively to the injector, in which case it may be fixed to the injector itself, or mounted in the axis of the plug *b*, as shown in Figs. 1 and 2; but a preferable construction is shown in Fig. 5, where the baffle *g'* is mounted eccentrically on the plug *b* in such manner as to be situated at a distance from the mouth of the jet when the chamber *c* is fully open and to gradually move closer 110 to the jet in proportion to the angular closing movement of the plug, while remaining directly opposite the jet throughout all its movements.

The carbureting chamber may also occasionally receive air through apertures *h* in plug *b* from the normally closed spring valve *i*, which acts automatically; but only when the engine meets with a relatively low resistance and starts to race, as before explained, above the normal high or low speed for which it is set by throttle. The racing produces a violent suction that raises the valve, and thus checks excessive flow of fuel 125 while also admitting more air. The auto- 130

matic air valve is thus seen to admit more air as the engine speed rises above any normal high or low speed, while the positive air valve *e* provides a relatively larger air opening for the lower normal speeds than for the higher normal speeds.

The chamber *j* through which the carbureting liquid passes on its way from the reservoir *l* to the jet *d* is surrounded by a heating chamber *k* which is traversed by a current of hot exhaust gases or by a stream of hot water supplied by the water circulation of the engine. This heating, by increasing vaporization, facilitates carburation at low speed.

The evident advantages of the device are its simplicity, strength, precision, and absolute reliability, as the ratio of the two valve areas depends solely upon the angular set of a solid plug in its casing.

What I claim as my invention and desire to secure by Letters Patent of the United States, is:

1. The combination with a carbureter comprising a carbureting chamber having an air inlet port and an opposite mixture outlet port, and a fuel inlet or jet with its fuel exit situated inside of such carbureting chamber between the said inlet and outlet ports, to deliver fuel at a point within such chamber into the body of the fluid stream that rushes directly from said inlet port to said outlet port and at a rate depending upon the degree of vacuum created in such chamber by the pumping action of the engine; of a slide having an air inlet opening and a mixture outlet opening corresponding, respectively, to said air inlet port and to said mixture outlet port and adapted to act as a combined air and mixture slide for simultaneously closing both of said ports; said valve openings being so shaped that the ratio of corresponding air port inlet and mixture outlet decrements shall be smaller than unity in the first closing stages and then larger than unity in the later closing stages, but still sufficiently restrained to preserve a certain uncovered opening in the air inlet port when the mixture outlet port has moved to full closure.

2. The combination with a carbureter comprising a carbureting chamber having an air inlet port and an opposite mixture outlet port, and a fuel inlet or jet with its fuel exit situated inside of such carbureting chamber between the said inlet and outlet ports, to deliver fuel at a point within such chamber into the body of the fluid stream that rushes directly from said inlet port to said outlet port and at a rate depending upon the degree of vacuum created in such chamber by the pumping action of the engine; of a slide having an air inlet opening and a mixture outlet opening corresponding, respectively, to said air inlet port and to

said mixture outlet port and adapted to act as a combined air and mixture slide for simultaneously closing both of said ports; said air slide opening having marginal vacant surface elements which are covered by an edge of the air port wall when the said slide is in extreme open or closed position and which are uncovered while the slide is being moved from one extreme position to the other.

3. In a carbureter for internal combustion engines using liquid fuel, the combination of a shell or casing; a valve mounted therein, said valve being provided with an opening extending therethrough communicating at its opposite ends with a port extending to the motor and with a port opening to the atmosphere; a jet for the fuel to be vaporized extending into the opening formed in the valve; and a baffle carried by said valve, the baffle being located eccentrically to the axis of the valve whereby as the valve is rotated to open the port which communicates with the motor the baffle will be moved away from the mouth of the injector.

4. The combination with a carbureter comprising a casing having an inside chamber formed as a body of revolution with an air inlet port and an opposite mixture outlet port formed through such casing, and a jet for conveying liquid fuel to a point within such chamber at a rate dependent upon the degree of vacuum created in such chamber by the pumping action of an engine; of a plug adapted to fit and turn in such chamber and also having an internal chamber with inlet and outlet openings adapted to register with the inlet and outlet ports of the said surrounding casing; the outlet opening in said plug and the two ports in said casing being similar in outline, and the inlet opening in said plug being of different outline adapted to close the air port at a lower rate in its initial closing movements and a higher rate in its final closing movements than it would if made of the same outline as the other slide opening and ports, said final closing movements falling short of full closure of the air port when the said mixture outlet is practically closed to form a finite air inlet corresponding to a practically infinitely small mixture outlet.

5. The combination with a carbureter comprising a casing having an inside chamber formed as a body of revolution with an air inlet port and an opposite mixture outlet port formed through such casing, and a jet for conveying liquid fuel to a point within such chamber at a rate dependent upon the degree of vacuum created in such chamber by the pumping action of an engine; of a plug adapted to fit and turn in such chamber and also having an internal chamber with inlet and outlet openings adapted to register with the inlet and outlet

ports of the said surrounding casing; the outlet opening in said plug and the two ports in said casing being similar in outline, and the inlet opening in said plug being of different outline adapted to close the air port at a lower rate in its initial closing movements and a higher rate in its final closing movements than it would if made of the same outline as the other slide opening and ports, said final closing movements falling short of full closure of the air port when the said mixture outlet is practically closed to form a finite air inlet corresponding to a practically infinitely small mixture outlet, such finite area being adapted to reserve a radial air port area or channel for the passage of the fuel jet.

6. The combination with a carbureter comprising a casing having an inside chamber formed as a body of revolution with an air inlet port and a mixture outlet port formed through such casing, and a jet for conveying liquid fuel to a point within such chamber at a rate dependent upon the degree of vacuum created in such chamber by the pumping action of an engine; of a plug adapted to fit and turn in such chamber and also having an internal chamber with inlet and outlet openings adapted to register with the inlet and outlet ports of the said surrounding casing; the outlet opening in said plug and the two ports in said casing being similar in outline, and the inlet opening in said plug being of a different outline adapted to form marginal recesses or vacancies in the air slide at points which are covered by the wall of said casing when the said air inlet is in its extreme positions, but which are uncovered as the said air slide is moved from its extreme open position to its extreme closed position to

thus retard but not wholly prevent the closing effects of the valve.

7. The combination with a carbureter comprising a casing having an inside chamber formed as a body of revolution with an air inlet port and a mixture outlet port formed through such casing, and a jet for conveying liquid fuel to a point within such chamber at a rate dependent upon the degree of vacuum created in such chamber by the pumping action of an engine; of a plug adapted to fit and turn in such chamber and also having an internal chamber with inlet and outlet openings adapted to register with the inlet and outlet ports of the said surrounding casing; the outlet opening in said plug and the two ports in said casing being similar in outline, and the inlet opening in said plug being of a different outline adapted to form marginal recesses or vacancies in the air slide at points which are covered by the wall of said casing when the said air inlet is in its extreme positions, but which are uncovered as the said air slide is moved from its extreme open position to its extreme closed position to thus retard but not wholly prevent the closing effects of the valve, such air inlet outline being, furthermore, formed to reserve vacancies in parts of the air slide surface that is uncovered in the extreme closed position of the slide but that are covered by the wall of the said casing in its extreme open position.

In testimony whereof I affix my signature in presence of two witnesses.

CHARLES HENRI CLAUDEL.
